STAND FOR ICE FISHING ROD

Ferdinand F. Salzmann, Box 5332,
Madison, Wis. 53705

Filed Mar. 19, 1969, Ser. No. 16,331

Term of patent 14 years

Int. Cl. D22—08

U.S. Cl. D22—22

FIG. 1

FIG. 2

FIG. 3

FIG. 1 is a frontal perspective view of a stand for ice fishing rod embodying my new design;

FIG. 2 is a front elevation view of my stand for ice fishing rod; and

FIG. 3 is a side elevation view of my stand for ice fishing rod.

The portion shown in broken lines in FIG. 1 represents an ice fishing rod and is not part of my design.

I claim:

The ornamental design for a stand for ice fishing rod, as shown and described.
